W. F. ARZINGER

LUMINOUS PENDANT

Filed Aug. 5, 1921

William F. Arzinger
Inventor
By his Attorneys
William & Patchard

UNITED STATES PATENT OFFICE.

WILLIAM F. ARZINGER, OF JERSEY CITY, NEW JERSEY.

LUMINOUS PENDANT.

Application filed August 5, 1921. Serial No. 439,996.

To all whom it may concern:

Be it known that I, WILLIAM F. ARZINGER, a citizen of the United States, and a resident of Jersey City, county of Hudson, 5 State of New Jersey, have invented certain new and useful Improvements in Luminous Pendants, of which the following is a specification.

My invention relates to luminous pendants such as are particularly adapted to be attached to the pull cords of electric switches in order that their location may be readily determined in the dark.

An important object of the invention is 15 to provide a device of the above mentioned character in which I am enabled to obtain a maximum intensity of luminosity with a minimum amount of luminous material.

Another object of the invention is to provide in a luminous pendant a simple and efficient means by which the same may be readily attached to a pull chain.

A further object of the invention is to provide a luminous pendant the elements 25 of which are simple in construction, inexpensive to manufacture, and easy to assemble.

Other objects of the invention will become apparent from the following description 30 taken in connection with the accompanying drawings, in which:

Figure 1 is an elevation of the device embodying my invention.

Figure 2 is a central vertical sectional 35 view of the device.

Figure 3 is a face view of a blank from which the locking device is formed.

Figure 4 is a perspective view of one end 40 of the pendant.

Figure 5 is a perspective view of a carrying sheet.

In the drawings, wherein for the purpose of illustration is shown the preferred form 45 of my invention, the numeral 10 indicates a central tubular element having at one end thereof a head or base 11, provided with a peripheral flange 12. Around the central tubular element 10 is disposed a globe or shell 13, which may be formed of any suitable translucent material such for example 50 as celluloid but preferably constructed of glass. The globe or shell 13 it will be noted is bilged intermediate its ends in order that the luminous material hereinafter referred 55 to may be maintained well out of contact

with the globe so as to prevent any sticking or adhering of one to the other as might be caused by the presence of more or less moisture within the globe.

The luminous material above referred to 60 is in the form of a coating 14, deposited upon the surface of a carrying sheet 15, which is preferably formed of a suitable paper. In constructing the carrying sheets 65 15 I prefer to employ relatively large sheets of material which when coated with the luminous material are cut into proper lengths and widths. Each of the strips thus cut from a relatively large sheet of material is then rolled into a cylinder as shown 70 clearly in Figure 5, into which is inserted the tubular member 10. The next step in assembling the device resides in placing in position the globe or shell 13, the globe or shell being so positioned as to contact with 75 the head 11 of the tubular member 10 and surround the carrying sheet 15 as clearly shown in Figure 2.

The various elements thus far described 80 are held in their respective positions by means of a cap-plate 16 which is formed from a blank 17 comprising a central portion 18 having an opening 19 formed therein and provided diametrically with arms 20, the ends of which are spread as shown at 21 85 and provided with notches 22. In order to form the cap-plate the arms 20 are bent to bring the ends of the same into proximity with each other and to bring the notches into registration with each other to form an opening 23. The cap-plate 16 thus formed from the blank 17 is locked in position by upsetting or flanging the end of the tubular member 10 over which the cap-plate is placed, to form a bead 24. The device 90 embodying my invention is adapted to be connected to the ordinary pull chain 25 comprising a plurality of balls 26 strung upon a wire 27 or otherwise suitably connected together, and in order to effect this connection 100 the chain 25 is passed through the tubular element 10 whereupon the arms 20 of the cap-plate 16 are sprung apart to permit the passage of the ball 26 at the end of the chain. As the ball 26 at the lower end of the chain 105 25 passes the opposite ends of the arms 20 they by reason of their inherent resiliency spring into their respective positions shown in Figure 2, thereby locking the device as a whole to the chain 25.

Having thus described my invention, I claim:

1. A pendant adapted for connection with a pull chain comprising a tubular member adapted to receive the pull chain, a tubular shell surrounding said tubular member, a carrying sheet having luminous material thereon, the carrying sheet being interposed between said tubular member and shell, and 10 yieldable means for engaging one end of the pull chain for securing the pendant to the same.
2. A pendant comprising a central member, a shell disposed about said central member and having a bilged portion spaced from the central member, a carrying sheet having luminous material thereon, the carrying sheet being disposed between said central member and shell and spaced from 20 both the central member and shell.
3. A pendant adapted to be connected to a pull cord comprising a central tubular member adapted to receive the pull cord, a head carried by said tubular member, a 25 shell surrounding said tubular member and

having engagement with said head, luminous material carried within said shell, a cap-plate carried by said tubular member and having engagement with said shell, a pair of arms carried by said cap-plate, the 30 arms being bent upon themselves to form locking elements adapted to engage the pull cord whereby the pendant is locked upon the same.

4. A pendant comprising a shell, a central member arranged within said shell, said member being in the form of a tube having a head seated upon one end of said shell and forming a closure therefor, a cap plate carried by said central member and arranged upon the opposite end of said shell, said central member being clenched over 40 said cap plate to retain the same in position upon said shell, and luminous material disposed intermediate said shell and central member.

In testimony whereof, I have affixed my signature to this specification.

WILLIAM F. ARZINGER.
